ABSTRACT OF THE DISCLOSURE

An improvement for reproducing onto a copy paper the latent image of an original which has been produced by the Reduced Layer Formation Process (RLF), which comprises treating the original with oleic acid, transferring a latent oil image on the original onto a copy paper and rendering the transferred latent oil image on the copy paper visible.

This invention relates to an improvement for the reproduction of a latent oil image of an original document onto a copy paper and more specifically to an improved process utilizing oleic acid to form the latent oil image.

The RLF process developed by Abrams Games, which is the subject of Dutch patent application 6,415,234, is one of the methods utilized to reproduce original designs such as letters, printed or duplicated matter, photographs, drawings or other specially prepared originals whether on paper or other surfaces. The RLF process is based on the discovery that the production of an original design may decrease the absorbency of the surface to liquids in the image areas defining the design and that the resultant differential absorbency as between the image and non-image areas can be utilized in the production of copies.

The range of liquids which can be differentially absorbed in the RLF process depend on the nature of the surface and of the image. In general, the liquids utilized are colorless so as not to perceptibly mark the original, have little or no odor and are nontoxic. Suitable liquids include, for example, water, milk, diethylene glycol monethyl ether, glycerol triacetate, glycerine, diethyl and dimethyl phthalates, and dilute benzoic acid.

One method in accordance with the RLF process comprises positioning a layer of a suitable liquid between the design bearing surface of the original and a second surface in contact with the original. The effect of the differential absorption is that the layer of liquid is formed into a pattern corresponding to the original design and when the second surface is removed, it carries with it a liquid pattern defining a mirror image of the original design.

The resultant image on the copy paper is then rendered visible by the utilization of toner particles with the application of heat. The powders utilized for the development of the image on the copy paper are resins, waxes, shellacs, dyes, particles of metal and the like.

While the Games patent literature list a wide variety of materials which are operable in the RLF process, the literature appears to emphasize the use of specific oils for a specific type of original.

It is an object of this invention to provide and disclose a universal oil for utilization in the RLF process operable with a variety of originals.

2

Other objects and a fuller understanding of the invention may be ascertained from the following description and claims.

It has been found that oleic acid is substantially a universal oil for the treatment of most originals in the RLF process. The oleic acid may be dissolved in alcohol, for example, 10-20% by weight of oleic acid, and sprayed onto the image bearing original. Baker Analyzed Reagent 9400 was the alcohol utilized. It is composed of 95 parts by volume of an alcohol made from a mixture of 95 parts by volume of ethanol and 5 parts by volume of methanol; and 5 parts by volume of 2-propanol. Any of the denatured alcohol compositions are operable in the inventions. In addition, other lower alkyl alcohols may be substituted for isopropanol and ethanol. The latent image on the copy paper is subsequently developed by means of toners in accordance with the RLF process. In the alternative, the oleic acid may be applied undiluted to the original by means of a roller and the latent transferred image developed by means of toners. In addition, the oleic acid may be utilized to serve as the carrier for an iodine precursor which, when transferred to the copy paper, can be developed by a starch solution. The latter method is the subject matter of copending patent application 716,236 filed Mar. 26, 1968 by F. J. Stryker et al.

Illustrative examples of my process are set forth in Examples 1 and 2 below:

EXAMPLE 1

30 Ten to twenty lambdas of oleic acid are applied to a flat metal plate. A suitable roller, e.g., a comet roller (urethane composition by Samuel Bingham Co.) is rolled over the plate spreading the oleic acid over a surface of approximately 700 square centimeters. The roller is then rolled over the image containing original which allows the roller to pick up a reversed, "wrong reading," RLF image on its surface, which when rolled onto a sheet of copy paper becomes, "right reading." The image is developed on the copy paper with any suitable toner.

EXAMPLE 2

40 A small amount of a solution of 15% oleic acid, e.g., 1 to 3 milliliters, is sprayed onto the image bearing original. The image is then transferred with a comet roller to a copy paper. The image is developed on the copy paper in accordance with the procedure described in Example 1.

45 Oleic acid has enabled me to reproduce typings from a variety of bond paper originals. In addition, oleic acid will reproduce sharp images from offset press generated originals, and letterpress originals from magazines.

50 Although I have described my invention with a certain degree of particularity, it is understood that the foregoing is made to set forth the best mode contemplated in carrying out the invention and not as a limitation thereof, in that many modifications may be made in the combination of proportions or in the application of the oil containing solutions to the surfaces, without the vitiation of the operability of the invention.

55 Having described my invention, I claim:

1. In a process for the reproduction of a latent oil image from an original onto a second-surface comprising: the application of a liquid to the surface of the original having a differential absorbency as between the image and

nonimage areas thereby forming a liquid pattern corresponding to the image, contacting the original with the second-surface whereby a layer of the liquid pattern corresponding to the original image is transferred to the second-surface and rendering the transferred image visible, the improvement wherein the applied liquid is oleic acid.

2. The improvement of claim 1 wherein the applied liquid is a solution consisting of 10-20% by weight of oleic acid dissolved in an alkyl alcohol having 1-3 carbon atoms.
